BATHTUB

Oscar G. Watt, Tulsa, Okla.

Application June 4, 1938, Serial No. 211,894

6 Claims. (Cl. 4—4)

This invention relates to improvements in a combination bath tub and sitz bath.

The conventional sitz bath heretofore known for abdominal and pelvic ailments has not come into common use due to the fact that water in a separate sitz bath would be displaced and overflow on the floor when a person sat in the bath. Obviously, any overflow would cause detrimental damage to the floor and construction of the building where the separate sitz bath was installed.

It is therefore an important object of this invention to provide a combined sitz bath and bath tub of such construction that any excess overflow from the sitz bath flows into the bath tub, and wherein the sitz bath, disposed in the bath tub in such a manner that a full length bath tub is provided without any substantial increase in the length of the combined fixture.

A further important object of this invention is to provide a combined sitz bath tub and bath tub of such construction that it is economical in manufacture and capable of easy installation in modern housing constructions.

And still another important object of this invention is to provide a combined sitz bath and bath tub having an apron of such construction so that it forms a compartment so that substantially all piping are encased within the compartment, thus eliminating any unsightly disclosures in the bathroom.

Other objects and advantages of my invention will be evident from the following detailed description read in conjunction with the accompanying drawings which illustrate one form of my new invention.

In the drawings:

Fig. 1 is a perspective view with portions cut away showing the combined sitz bath and bath tub.

Fig. 2 is a sectional elevational view of the improved device.

Fig. 3 is a plan view of the device.

Referring to the drawings in detail, the combined bath tub and sitz bath comprises an enameled metal casting or body member 2, forming a hollowed-out bowl or tub 4, of such depth and length to accommodate a human body in the normal position of a plunge bath. The bowl 4 at one end thereof in a substantially medial vertical position has integrally cast therewith an outwardly extending transverse partition 6, having a horizontal portion 8 and an angled portion 10. The angled portion 10 is disposed in the bowl 4 at approximately a 45 degree angle with

the horizontal, as will be apparent from an inspection of Fig. 2. The outer end of the partition is rounded at 12. The partition 6 is integrally secured or cast with the inner sides or walls 14 and 16 of the tub 4. It will be apparent that the angled partition 6 in cooperation with the side walls 14 and 16 form a sitz bath compartment 18 disposed within the tub 4 as an integral part of the body member 2.

The sitz bath compartment 18 is additionally supported by an integral upright member or partition 19 disposed between the partition 6 and the base 21 of the tub 4. This partition 19 in conjunction with the partition 6 obviously separates the bath tub compartment 4 from the sitz bath compartment 18. It will be apparent that with this construction the bath tub compartment 4 allows ample room for the bather, and furthermore, the space beneath the sitz bath provides for ample leg room in the tub 4. This is due to the particular "space saving" disposition of the angled portion 10, extending upwardly and into the bath tub compartment 4 in such a manner to allow for sufficient space beneath the sitz bath compartment 18. It has been found that with this construction it is only necessary to add one foot to the length of a conventional bath tub to include a sitz bath.

The end wall 20 of the bowl 4 opposite the sitz bath 18 is constructed at an angle to the horizontal as in conventional bath tub construction. The side walls 14 and 16 of the tub 4 at their upper portions extend outwardly to form horizontal flanges or aprons 22 and 24, respectively. As clearly shown in Fig. 1, the apron 24 terminates in a vertical outer wall 26 disposed in spaced relation to the wall 16 to provide a compartment 28. The side wall portions and the end walls 23 and 25 of the body member 2 forming the exterior of the sitz bath compartment 18 are of a height greater than the wall portions forming the tub compartment 4, in order to allow for a substantial depth to the sitz bath and also to prevent any detrimental overflow of water over the sides of the body member 2. The body member 2 between the sitz bath 18 and the tub 4 is constructed with an angled or sloping wall portion 30.

The compartment 28 formed by the walls 16 and 26 is of a width sufficient to substantially house the piping and fittings for the combined sitz bath and bath tub, and thus prevent an unsightly appearance. As clearly shown in Fig. 1, a main drain pipe 32 extends from a source (not shown) into the compartment 28. The horizon-

tal portion 8 of the sitz bath is recessed to receive a centrally disposed nipple 34 in communication with the main drain pipe 32 by drain conduits 36 and 38 coupled together by the T-fitting 40. Regulation of the drain outlet for the sitz bath compartment 18 is controlled by a drain valve 42 extending upward from the T-fitting 40, with the top portion 43 supported above the apron 24. The bath tub compartment 4 is provided with a drain nipple 44 in communication with the main drain pipe 32 by a pipe or conduit 46 coupled thereto by the T-fitting 48. Regulation of the bath tub drain 44 is controlled by a drain valve 50 disposed adjacent the valve 42 and constructed in a similar manner.

The hot and cold water faucets 52 and 54, respectively, are mounted in the apron 24 and are in communication with a source of water supply (not shown) by the conduits 56 and 58, respectively, housed in the compartment 28. A two-way valve 60 adjacent one of the faucets is likewise mounted in the apron 24. The valve 60 is in communication with the nipple 34 of the sitz bath by a conduit 62. A conduit 64 connects the valve 60 with an inlet 66 for the bath tub compartment 4. The valve 60 is in communication with the water faucets 52 and 54 by the conduits 68 and 70, respectively. It will be obvious that manipulation of the handle 72 of the valve 60 will allow the flow of water either into the sitz bath compartment 18 or the bath tub 4, as may be desired. Conventional overflow drains (not shown) for both the sitz bath and tub may be provided. The outer wall 26 may have a door (not shown) in order to allow for access to the fittings within the compartment 28.

From the foregoing, it will be apparent that a bath tub is constructed with a sitz bath disposed therein in such a manner to provide for sufficient room for a comfortable plunge bath without any exaggerated construction of the bath tub so that it could not be readily installed in a modern bathroom. Furthermore, the combined bath tub and sitz bath not only provides for a plunge bath, but has an easily accessible sitz bath allowing separate bathing of the lower abdominal portions of the body so that any detrimental overflow of the sitz bath due to the displacement of the water in the sitz bath will be taken care of by the bath tub.

It is believed that the construction, arrangement of parts, and the operation of the valve will be clear to those skilled in the art and it is obvious that changes may be made in the details disclosed without departing from the spirit of the invention as expressed in the claims.

What I claim is:

1. In combination with a bath tub, a sitz bath rigidly secured within the bath tub, and comprising a partition extending outwardly from a substantial vertical medial point of an inner end wall of the bath tub, said partition having an outer portion extending upward at an angle to the horizontal, a support partition rigidly secured beneath the first mentioned partition, said support partition so positioned with respect to the angular portion to provide a space beneath the first mentioned partition whereby a full length bath tub is provided, a flange extending outwardly from the top of the side wall of the tub, and terminating in a vertical outer wall disposed

in spaced relation with the side wall of the tub to provide a compartment, control means for the water supply to the bath tub and sitz bath mounted in the flange, said compartment substantially housing the pipes and fittings for the control means.

2. A bath tub comprising a body member having a tub compartment, an angled partition constituting a sitz bath compartment disposed within the tub compartment, an upright partition beneath the sitz bath and cooperating with the walls of the tub compartment for rigidly supporting the sitz bath, said upright partition cooperating with the angled partition to provide a space beneath the sitz bath whereby a full length tub compartment is provided, an apron extending outwardly from the top of the side wall of the tub, and terminating in a vertical outer wall disposed in spaced relation with the side wall of the tub to provide a compartment, control means for the water supply to the bath tub and sitz bath mounted in the apron, said compartment substantially housing the pipes and fittings for the control means.

3. In combination with a bath tub, a sitz bath rigidly secured within the bath tub, and comprising a partition extending outwardly from a substantial vertical medial point of an inner end wall of the bath tub, said partition having an outer portion extending upward at an angle to the horizontal, a support partition rigidly secured beneath the first mentioned partition, said support partition so positioned with respect to the angular portion to provide a space beneath the first mentioned partition whereby a full length bath tub is provided.

4. A bath tub comprising a body member having a tub compartment, an angled partition constituting a sitz bath compartment disposed within the tub compartment, an upright partition beneath the sitz bath and cooperating with the walls of the tub compartment for rigidly supporting the sitz bath, said upright partition cooperating with the angled partition to provide a space beneath the sitz bath whereby a full length tub compartment is provided.

5. A bath tub comprising a body member having a tub compartment, an angled partition constituting a sitz bath compartment disposed within the tub compartment, an upright partition beneath the sitz bath and cooperating with the walls of the tub compartment for rigidly supporting the sitz bath, said upright partition cooperating with the angled partition to provide a space beneath the sitz bath whereby a full length tub compartment is provided, drain means for the tub compartment, means for controlling the drain means, drain means and control means therefor for the sitz bath compartment separate from the tub compartment.

6. A bath tub in combination with a sitz bath constructed therein, a horizontal apron extending outward from the wall of the bath tub and terminating in a vertical outer wall disposed in spaced relation to the wall of the tub to provide a compartment, control means for the bath tub and sitz bath mounted in the apron, said compartment substantially encasing the conduits and fittings for the control means.
